Patented Jan. 13, 1925.

UNITED STATES PATENT OFFICE.

ANNON W. HOLT, OF MENOMONIE, WISCONSIN.

DOOR LATCH.

Application filed December 27, 1921. Serial No. 524,901.

To all whom it may concern:

Be it known that I, ANNON W. HOLT, a citizen of the United States, residing at Menomonie, in the county of Dunn and State 5 of Wisconsin, have invented certain new and useful Improvements in Door Latches; and I do hereby declare the following to be a full, clear, and exact description of the invention, such as will enable others skilled 10 in the art to which it appertains to make and use the same.

My present invention relates to door latches of the type disclosed and broadly claimed in my U. S. Letters Patent No. 15 1,387,888 issued August 16, 1921, and has for its object to improve the same in the several particulars hereinafter noted.

To the above end, the invention consists of the novel devices and combinations of 20 devices hereinafter described and defined in the claims.

In the accompanying drawings, which illustrate the invention, like characters indicate like parts throughout the several 25 views.

Referring to the drawings:

Fig. 1 is a fragmentary view, principally in vertical section, taken through a door and mortise latch having the invention embodied 30 therein, said invention being designed for a door hinged to swing inward;

Fig. 2 is a view corresponding to Fig. 1 with the exception that the inner knob has been shifted into a position to lock the operating shaft;

Fig. 3 is a perspective view of the operating shaft;

Fig. 4 is a view, principally in transverse section, taken on the line 4—4 of Fig. 2;

Fig. 5 is a perspective view of the inside 40 knob;

Fig. 6 is a view, principally in transverse section, taken on the line 6—6 of Fig. 1;

Fig. 7 is a fragmentary view of the inside 45 side escutcheon;

Fig. 8 is a view showing the invention modified for use on a door hinged to swing outward;

Fig. 9 is an elevation of the knob shown in 50 Fig. 8 with some parts broken away and sectioned; and

Fig. 10 is a modification showing a different arrangement for releasably holding the inside knob on the shaft.

Referring first to the invention shown in Figs. 1 to 7, inclusive, the numeral 11 indicates a door which may be assumed to be hinged for outward swinging movement and provided with a mortise latch 12. This latch 12 is provided with the customary sleeve-like latch bolt actuating member 13 having an axial passageway that is square in cross section to receive a correspondingly formed knob equipped operating shaft. Formed with the member 13 are the ordinary oppositely projecting latch bolt operating lugs or pins 14 and which member is yieldingly held in an intermediate position by a spring, not shown. As is well known, the latch bolt of such a latch is spring-projected and arranged to be cammed into a retracted position by engagement with a latch plate on the door frame, during the closing movement of a door, without turning the knob-equipped operating shaft. To retract the latch bolt, it is necessary to turn the knob-equipped shaft and thereby cause a turning 70 movement of the member 13 and its lugs 14 which are connected to said latch bolt. The parts thus far described are of standard and 75 well known construction.

The member 13 is held in a latch casing against axial movement, by co-operating flanges 15 on said member and latch casing, but is free to turn. Secured to each side of 80 the door 11, is an escutcheon 16 having an annular socket 17 axially aligned with the member 13 and a bore in the door 11 and apertures in the escutcheons 16. As shown, the sockets 17 are independently formed in 85 respect to the escutcheon 16 and are secured thereto by contracting their inner end portions to afford shoulders in said escutcheons inserting the same through the apertures and then upsetting the same on the inner 90 faces of said escutcheons.

The operating shaft, heretofore mentioned and on which the member 13 is mounted, is indicated by the numeral 18, and on the ends thereof, are applied outer and 95 inner knobs 19 and 20, respectively, the neck portions of which extend into the sockets 100

17. Both knobs 19 and 20 are formed from pressed sheet metal and have rigidly secured in their neck portions, case cores 21 and 22, respectively.
- 5 The core 21 is of standard construction and has an axial passageway, which is square in cross section, to receive the outer end of the operating shaft 18 for common turning movement therewith, but with freedom for axial sliding movement thereon. A screw 23 inserted through aligned bores in the neck portion of the knob 19 and the core 21 has screw-threaded engagement with any one of a plurality of transverse longitudinally spaced bores 24 in the operating shaft 18. By means of these bores 24, the outer knob 19 may be adjustably connected to the shaft 18, thereby making the same applicable to doors of different thicknesses.
- 10 The operating shaft 18 is held against end-wise movement, in respect to the door 11, by the neck portion of the knob 19, which engages the shoulder on the respective socket 17, and a pin 25 which extends transversely through the operating shaft 18 and has engagement with the member 13.
- 15 The core 22 which forms an important part of my present invention, is provided with an axial passageway which is square in cross-section and in which the inner end of the operating shaft 18 slidably extends for common rotation therewith. This core 22 is secured to the neck portion of the inner knob 20 by a screw 26. To releasably connect the knob 20 to the operating shaft 18 in different longitudinal adjustments thereon, there is mounted in a recess 27 in the core 22, a V-shaped spring 28, the intermediate portion of which normally projects into the axial passageway in the said core for engagement with any one of a plurality of longitudinally spaced transverse lock notches 29 formed in the several sides of the operating shaft 18.
- 20 The outer end of the core 22 is reduced to form a hub 30 which extends outward of the neck portion of the knob 20 and has formed therewith, a pair of diametrically opposite lock lugs 31 and a pair of diametrically opposite stop lugs 32, located 180 degrees from said lock lugs. It will be noted that the lock lugs 32 are at the inner end of the hubs 30 and the stop lugs 32 are at the outer end thereof and axially spaced therefrom. The stop lugs 32 are located inward of the inner escutcheon 16 and are arranged to engage the inner end portion of the respective socket 17 as a positive stop to limit the outward axial movement of the knob 20 on the shaft 18.

25 To secure the operating shaft 18 against rotation, and thereby secure the door 11 locked close, there is formed in the inner escutcheon 16 and the attached portion of the respective socket 17, a pair of diametri-

cally opposite lock notches or seats 33 adapted to receive the lock lugs 31 when the knob 20 is moved axially on the operating shaft toward the door 11 and into a position, as shown in Fig. 2. With the inner knob 20 thus adjusted, the door 11 cannot then be opened from the outside for the reason that the knob 19 is held against turning movement by the interlocking engagement of the lock lugs 31 with the lock seats 33. 75

To close and lock the door 11 from the inside, the occupant of the room takes hold of the knob 20, swings the door to a closed position, which causes the spring projected latch bolt to automatically interlock with the latch plate on the door frame in the customary manner. Then by a pressure on the knob 20 toward the door the spring 28 is cammed out of the engaged lock notch 29 and said knob moved axially on the operating shaft 18 which carries the lock lugs 31 into interlocked engagement with the lock notches 33 thereby prevents the door from being opened from the outside. 80

85 To unlock the door 11, it is only necessary for the occupant of the room to draw the knob 20 axially away from the door 11 to slide the same on the operating shaft 18 and thereby withdraw the lock lugs 31 from the lock notches 33 to permit either of knobs 19 and 20 to be turned and thereby withdraw the latch bolt from the latch plate on the door frame and permit the door to be opened. 90 During the outward sliding movement of the knob 20 on the operating shaft 20, the same is stopped by the engagement of the spring 28 with the lock notch 29 in the respective side of the operating shaft 18, which properly positions the lock lugs 31 and the stop lugs 32 to permit free rotation of the hub 30 in the respective escutcheon 16. Further outward movement of the knob 20, which would tend to cam the spring 28 out of the engaged lock notch 29, is prevented by the engagement of the stop lugs 32 with the respective socket 17. 95

100 In assembling the door latch, the screws which hold the inner escutcheon in position are temporarily omitted so that said escutcheon may be held at an angle to permit the stop lugs 32 to be inserted through the lock notches 33. After the inner escutcheon 16 is secured in position by its screws, the latch mechanism will prevent the knob 20 from being turned into a position in which the stop lugs 32 will register with the lock notches 33 and thereby render said stop lugs 105 inoperative. 110

120 In case a child or other person should lock the door from the inside, and could not open the same, said door could be opened from the outside by taking out the screw 23 and removing the knob 19. With the knob 19 removed, the operating shaft 18 may be moved endwise toward the door 11 to with- 125 130

draw the lock lugs 31 from the lock seats 33 and then rotated to operate the lock mechanism and unlock the door.

When the knob 20 is adjusted as shown in Figs. 1 and 8, the door 11 can always be opened from the outside of the room by operating the knob 19 in the customary manner.

Referring now to the invention as shown in Figs. 8 and 9 the same is designed for use on a door hinged to swing outward. In this construction, a pair of diametrically opposite lock lugs 34 are formed on the outer end of the hub 30 and when the latch is unlocked, extend on the inside of the inner escutcheon 16. When closing the door, by taking hold of the knob 20, a continued pull on the knob after the door is closed will cause said knob to move axially on the operating shaft 18 and thereby carry the lock lugs 34 into interlocked engagement with the lock seats 33. A stop washer 35 is secured to the inner end of the hub 30 for engagement with the respective socket 17 to prevent the lock lug 34 from being drawn outward through the lock seats 33 and thereby permit the removal of the knob 20 from the operating shaft 18.

In the modification shown in Fig. 10, the spring 28 is mounted in a recess 36 formed in the operating shaft 18 and arranged to enter a lock notch 37 in the core 22.

The invention may be embodied in ordinary door latches now commonly used with very little work and expense simply by substituting the operating shaft 18 for the ordinary operating shaft, and in removing the core from one of the knobs and substituting the core 22 therefor. It will also be necessary to cut or otherwise form the lock seats 33 in the inner escutcheon 16.

What I claim is:

1. A latch having a latch bolt operating member, a shaft operating said member and positively held against endwise movement, and knobs both rotatable with the shaft, the one knob being positively held against axial movement and the other knob being axially movable toward and from said other knob from operative to inoperative positions.

2. A latch having a latch bolt operating member, a shaft operating said member and positively held against axial movement, and a knob on each end of the shaft and rotatable therewith, one of said knobs being secured to the shaft against axial movement thereon and the other of said knobs being axially movable on the shaft from operative to inoperative positions.

3. A latch having a latch bolt operating member, a shaft operating said member and positively held against axial movement, a knob on each end of the shaft and rotatable therewith, one of said knobs being secured to the shaft against axial movement there-

on and the other of said knobs being axially movable on the shaft from operative to inoperative positions, and yielding means for releasably holding the axially movable knob in a predetermined position on the shaft 70 against axial movement.

4. A latch having a latch bolt operating member, a shaft operating said member and held against endwise movement, and knobs both rotatable with the shaft, the one knob 75 being held against axial movement and the other knob being axially movable toward and from said other knob from operative to inoperative positions, said axially movable knob being provided with a removable core 80 having a lock element.

5. A latch having a latch bolt operating member, a shaft operating said member and held against endwise movement, and knobs both rotatable with the shaft, the one knob 85 being held against axial movement and the other knob being axially movable toward and from said other knob from operative to inoperative positions, said axially movable knob being provided with a removable core 90 having a lock element, and a stop element.

6. A latch having a latch bolt operating member, a shaft operating said member and positively held against endwise movement, 95 an escutcheon, and knobs both rotatable with the shaft, the one knob being held against axial movement and the other knob being axially movable toward and from the knob, said axially movable knob and the escutcheon having co-operating separable 100 interlocking elements for holding said shaft and knobs against rotation.

7. A latch having a latch bolt operating member, a shaft operating said member and positively held against endwise movement, 105 an escutcheon, and knobs both rotatable with the shaft, the one knob being held against axial movement and the other knob being axially movable toward and from the knob, said axially movable knob and the escutcheon having co-operating separable 110 interlocking elements for holding said shaft and knobs against rotation, said axially movable knob also having a stop engageable with the escutcheon to limit its axial 115 movement in one direction.

8. A latch having a latch bolt operating member, a shaft operating said member and held against endwise movement, an escutcheon having a lock notch, and knobs both rotatable with the shaft, the one knob being held against axial movement and the other knob being axially movable toward and from the other knob, said axially movable knob having a removable core provided 120 with a lock lug arranged to enter the lock notch in the escutcheon during the axial movement of the axially movable knob in one direction to lock said shaft and knob 125 against rotation.

9. A latch having a latch bolt operating member, a shaft operating said member and held against endwise movement, an escutcheon having a lock notch, and knobs both rotatable with the shaft, the one knob being held against axial movement and the other knob being axially movable toward and from the other knob, said axially movable knob having a removable core provided

10 with a lock lug arranged to enter the lock

notch in the escutcheon during the axial movement of the axially movable knob in one direction to lock said shaft and knob against rotation, said removable core also having a stop arranged to engage the escutcheon to limit the axial movement of the axially movable knob in one direction. ¹⁵

In testimony whereof I affix my signature.

ANNON W. HOLT.
